UNITED STATES PATENT OFFICE.

FRED HIRSH, OF NEW YORK, N. Y.

ADJUSTABLE STRAP-FASTENING.

1,398,966.

Specification of Letters Patent.

Patented Dec. 6, 1921.

Application filed July 22, 1920. Serial No. 398,176.

To all whom it may concern:

Be it known that I, FRED HIRSH, a citizen of the United States, residing in the city of New York, in the county and State of New York, have invented a certain new and useful Adjustable Strap-Fastening, of which the following is a specification.

My present invention relates to an adjustable strap fastening, the object thereof being to provide a simple detachable fastener by means of which two straps or sections of strap, particularly in articles of wearing apparel or forming parts of a garment supporter, can be adjustably secured together.

The invention will be fully understood by reference to the accompanying drawings in which—

Figure 1 is a perspective view of the fastening, in one of its applications, and Figs. 2, 3, and 4 are similar views of its several parts, detached; Fig. 5 is a view showing in perspective a somewhat different application of the same fastening; and Fig. 6 is a longitudinal section through the fastening as shown in Fig. 5.

The fastening comprises a strap or section of strap or tape 1 which is folded back upon and secured to itself to form a permanent loop, a slotted plate or slide 2 with one closed slot 3 and a second slot 4 open centrally of its outer side which is mounted upon the looped strap by passing the free outer end of the latter through the closed slot and its inner or rear fold only back through the open slot of the plate, and a second strap or section of strap 5 which is adjustably secured to the looped strap by passing an end through the closed slot of the plate and then behind the looped strap and back through the open slot. The plate, having been mounted upon the looped strap, is slid along to the outer end of the loop where it is held fixed in position thereon, while the fastening is adjusted in length by drawing the second strap forward or back through the slots in the plate. The adjustment of the fastening is facilitated by tipping forward or outwardly the end of the looped strap, thereby relieving in large

measure the friction by which the other strap is held in the plate.

In Fig. 1, the looped strap is shown as sewed or otherwise permanently attached to an undergarment (one on each side thereof) at its waist-line, and in the slotted plate mounted upon this downwardly projecting loop is adjustably secured the upper end of a hose-supporter the double lower ends of which (not shown) are provided with the usual or any suitable fasteners. The fastening is particularly adapted for children's union suits, which can be sold with hose-supporters thereon and these supporters as well as the slotted plates can readily be detached whenever the garment is to be washed.

As shown in Fig. 5, the straps are attached to or form parts of the two ends of the waist-band of a garment.

What I claim as new, and desire to secure by Letters Patent, is—

1. An adjustable fastening device comprising, in combination, two straps or sections of strap one of which is folded back upon and secured to itself to form a permanent loop and a plate with one closed and one open slot which is detachably mounted upon the looped strap by passing both folds of the loop through the closed slot and the rear fold only back through the open slot and in which the other strap is adjustably held by being passed first through the closed slot and then behind the closed strap and back through the open slot of the plate.

2. An adjustable strap fastening comprising a strap which is folded upon itself and secured to the waist of a garment to form a downwardly extending loop, a plate having a closed and an open-sided slot which is detachably mounted upon the looped strap by passing both folds of the loop through the closed slot and the rear fold only back through the open slot, and a hose-supporter strap the upper end of which is passed first through the closed slot and then behind the looped strap and back through the open slot of the plate.

FRED HIRSH.
